UNITED STATES PATENT OFFICE.

CHARLES R. WHITMAN, OF YPSILANTI, MICHIGAN.

NUT-LOCK.

SPECIFICATION forming part of Letters Patent No. 228,964, dated June 15, 1880.
Application filed December 8, 1879.

To all whom it may concern:

Be it known that I, CHARLES R. WHITMAN, of Ypsilanti, in the county of Washtenaw and State of Michigan, have invented certain new and useful Improvements in Lock-Nuts; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a perspective view of my improved nut-lock. Fig. 2 is a vertical section. Fig. 3 is a detached view of the cap which rests upon the nut, and Fig. 4 is the ratcheted locking-ring or socket.

In the drawings, A represents a bolt, of the ordinary construction, except that it has a hole near the upper end on a line at right angles to its axis. A' is a nut fitting the screw-threaded end of the bolt, and may be either square or many-sided, as shall be preferred.

The cap B consists of a base, provided with a depending skirt or flange, b, upon two or more sides, the shape and size of the cap in plan corresponding substantially to the shape and size of the nut, so that the flange or flanges b will fit accurately the sides of the nut, the object being that the rotation of the nut upon the bolt shall carry with it the cap, and vice versa, under all circumstances.

b' is a flange projecting upwardly from the face of the cap, the hole through the cap and the flange being of such diameter as to fit closely over the bolt.

b² is a lug or hook projecting from the face of the cap to receive one end of the spiral spring C, said spring being made of steel wire or a highly-tempered brass wire.

D d is a locking-ring or socket mounted loosely upon the outer end of the bolt. The part D of this locking-ring is recessed upon its upper face and formed into a ratcheted seat, as shown plainly in Fig. 4.

The flange d projects from the lower face of the part D, for a purpose which will be explained.

50 The horizontal projecting flange d' is perforated to receive one end of the spiral spring

C, the flange being of greater diameter than the spring C, so as to afford a bearing-surface for said spring.

In practice I prefer to cast the locking-ring or socket with the hole d³ in it, to save the expense of drilling, and under ordinary circumstances I propose to make it of malleable iron.

E is a pin, of steel or highly-tempered wire fitting within the hole in the upper end of the bolt, and engaging with the ratchet-tee in the recess of the locking-ring or socket, the pin being of such length as to fit closely within the walls of the recess.

The operation of the device is substantial as follows: After the nut A' has been screwed upon the bolt as far as is practicable or desirable, the cap B, having the spring C and locking-ring or socket attached thereto, is placed upon the bolt, with the flange b inclosing the nut, and the pin E is inserted in the hole at the upper end of the bolt, first compressing the spring by pressing the socket toward the cap, so as to permit the pin to be inserted in position, when upon releasing the socket the tension of the spring will hold it ratcheted face in close contact with said pin. The socket or ring is then turned around with a wrench in the same direction as the nut has been, increasing the torsion of the spring and its consequent pressure upon the cap in the direction in which the nut has been turned to any desired extent.

From an examination of the drawings it will be readily understood that the action of the spring is twofold: first, by reason of its torsion it exerts a continuous pressure upon the cap B and the nut in the direction in which the nut is turned when screwing it upon the bolt; and, secondly, by reason of its pressure in the direction of the axis of the bolt it holds the ratcheted face of the locking-ring or socket in firm contact with the pin E, and thus prevents the said ring or socket and the upper or outer end of the spring from turning backward relative to the bolt.

Thus it will be understood that the nut cannot be loosened upon the bolt by jarring or otherwise accidentally; but, on the contrary, the torsion of the spring C will keep the nut in close contact with whatever part may be

cent to it, so that no looseness of parts occur by reason of wear or shrinkage, because the nut will constantly follow up the upon which it bears.

The device can be readily detached from bolt by pressing the locking-ring or socket and the nut, so as to permit the withdrawal of the pin E, as will be readily understood. Under some circumstances I may substitute the hook d a straight spur projecting at an angle from the cap, to serve simply as a stud, against which one bent end of the ring C may rest, or, as this cap is made of malleable iron, the straight spur may be bent over, so as to clasp the end of the spring. I prefer this latter construction because it avoids the liability of the cap and spring becoming separated from each other, in which latter case there will be increased liability of one of the parts being lost or misplaced in transportation and handling.

When preferred the cap B may be connected with downwardly-projecting spurs adapted to engage with the sides of the nuts instead of the flange b; but I prefer the construction shown because, among other reasons, it is better adapted to receive a wrench when it is desired to tighten the nut without removing the locking devices.

The objects of the projecting flanges are, first, to properly support the cap and locking-ring or socket upon the bolt, and, secondly, to prevent the spring from coming in contact with the bolt.

It will be seen that the cap B may be raised upward the upper end of the bolt, turned backward, and then replaced upon the nut, whereby the tension of the spring may be increased without moving the upper end of the spring relative to the bolt.

What I claim is—

1. In a nut-lock, the combination, with the bolt and the nut, of a ratcheted plate arranged to engage with the bolt, and a spiral spring, which surrounds the bolt and is connected at one end with the nut and at the other end with said ratcheted plate, whereby the tension of the spring may be increased after the nut has been screwed in place, and the tension of the spring may be reduced by forcing said plate toward the nut and turning it backward, substantially as set forth. 45

2. In a nut-lock, the combination, with the bolt and nut, of a spiral spring connected at one end with the bolt by means substantially as set forth, and the interposed cap B, connected with the spring and adapted to engage with and be rotated with the nut, substantially as set forth. 55

3. In a nut-lock, as a means for attaching a spiral spring to the bolt, the plate provided with ratchet-teeth and adapted to receive one end of the spring, and a pin, E, passing through the bolt and adapted to engage with the teeth of the ratcheted plate, substantially as set forth. 60

4. In a nut-lock, the combination, with the bolt and nut, of a spiral spring connected with the bolt by means substantially as set forth, and a cap, B, connecting the spring and the nut, and provided with a flange, b², interposed between the spring and bolt, substantially as set forth. 70

In testimony that I claim the foregoing I have hereunto set my hand this 1st day of December, 1879.

CHARLES R. WHITMAN.
